UNITED STATES PATENT OFFICE

FRED J. BULLIS, OF CHICAGO, ILLINOIS, ASSIGNOR TO AUTO SPECIALTIES MANUFACTURING COMPANY, OF SAN FRANCISCO, CALIFORNIA, A CORPORATION OF CALIFORNIA

JACK

Application filed June 12, 1936. Serial No. 115,603.

This invention relates to a jack or pushing apparatus, the general object of the invention being to provide a telescopic jack, with means for quickly moving the parts to a position where the jack will engage the object to be lifted when the full lifting effect of the jack will come into action to lift the object.

Another object of the invention is to provide frictional means for holding the screw parts against turning movement, with means for permitting such means to yield when necessary to prevent damage to the parts.

A further object of the invention is to provide a telescopic member for preventing rotation of the inner screw, with means for moving said member into inoperative position when said inner screw is to be returned to normal position.

Still another object of the invention is to provide a jack having a driving member centrally mounted in the housing and having means formed in the base of the housing upon which the driving member is journaled for maintaining the driving member in co-axial alignment in the housing.

A further object of the invention is to provide in a jack of the class described, means for holding a projectable member of the jack from rotation so that the same may be automatically extended from the jack housing when the device is operated, and including a spring actuated dog clutch releasable in either direction to prevent damage to the jack parts when the extensible member is in fully extended and fully collapsed position.

Still another object of my invention is to provide in a jack of the class described, means for normally preventing rotation of an extensible member whereby the same may be automatically projected upon operation of the jack, and which means is manually operable, as by inverting the jack, to permit rotation of the extensible member whereby the same may be rapidly run back to its normal position by hand and without operating the driving mechanism of the device.

This invention also consists in certain other features of construction and in the combination and arrangement of the several parts, to be hereinafter fully described, illustrated in

the accompanying drawings and specifically pointed out in the appended claims.

In describing my invention in detail, reference will be had to the accompanying drawings wherein like characters denote like or corresponding parts throughout the several views, and in which:

Figure 1 is an elevation of the improved jack, showing the same in extended position.

Figure 2 is an enlarged longitudinal sectional view through the jack.

Figure 3 is a section on line 3—3 of Figure 2.

Figure 4 is a view of the cup-shaped member in the bottom of the device.

Figure 5 is a bottom plan view of the washer or disk which fits in the cup-shaped member.

Figure 6 is a detail sectional view showing the means for detachably connecting the telescopic member with the washer or disk.

Figure 7 is a longitudinal sectional view showing a modification.

Figure 8 is a vertical section taken substantially along the line 8—8 in Figure 5.

In these views, 1 indicates a base and 2 a casing which is suitably fastened to the base. A gear 3 is rotatably mounted on the base, preferably through means of a depending part 4 of a cup-shaped member 5 which is fastened to the base by the screw 6 or the like, the gear being rotatably mounted on said part 4 with the cup-shaped part above the gear. This gear has formed therewith an upright tubular part 7 which is provided with internal screw threads 8 at its upper end.

The casing 2 rotatably supports the member 7. A pinion 9, mounted on a stub shaft 10 which is journaled in the lower part of the casing 2, meshes with the gear. A handle, such as shown at 11 in Figure 1, may be detachably connected with the stub shaft. An outer screw member 12 fits within the part 7 and has its exterior threads 13 engaging the threads 8 and this part 12 is provided with internal threads 14 which engage the exterior threads 15 of an inner screw member 16. This member 16 has attached thereto at its upper end the saddle 17 for engaging the object to be lifted. A ring 18 is carried by the

lower end of the member 12 and prevents said member 12 from passing entirely through the upper end of the member 7. A washer or disk 19 is arranged in the cup-shaped member 5 and a coiled spring 20 has its lower end resting upon said disk or washer and its upper end engages the upper portion of the member 12, said spring applying pressure to both the member 12 and to the disk or washer 19.

Ribs 21 are arranged in the cup-shaped member 5 and are disposed on the upper surface of the bottom thereof, while similar ribs 22 are formed on the under face of the disk 19, these ribs being adapted to be disposed in contacting engagement and tending to prevent rotary movement of the disk in the cup-shaped member. A telescopic key tends to prevent rotary movement of the inner screw 16, this key consisting of a hollow part 23 of square shape in cross section and a solid part 24 of similar shape, the part 24 sliding within the part 23 and the two parts being held against separation through projections 25 on the part 23 engaging grooves 26 in the part 24, the grooves having their upper ends closed. The part 23 passes through a square bore in a nut 27 which is screwed in the lower end of the inner screw 16 and the part 24 is provided with a headed projection 28 at its lower end which passes through a hole 29 in the center of the disk 19 so that the disk is loosely connected with the part 24. This part 24 also carries the cross pin 30 which is adapted to engage with the hooks 31 formed on the disk 19, the pin and hooks acting to lock the disk to the part 24, but when said part 24 is given a slight turning movement, in the direction of the arrow in Figure 5, the pin 30 will disengage the hooks 31 so that the part 24 and the pin can be moved away from the disk until the head 29 of the projection 28 strikes the disk. This will permit turning movement of the telescopic key and the inner screw 15 without turning the disk 19.

In the modification shown in Figure 7, the tubular part 7' is located within the outer screw 12' and said part 7' is threaded over its entire extent. The part 12' is interiorly threaded at its lower end and these threads mesh with the threads of the part 7'. In other respects, this form of the invention is similar to that above described.

55 As will be seen, the threads of the parts are such as to give the outer screw 12 a quick rectilinear movement when the gear 3 and its part 7 are rotated, while the inner screw has a slower movement when the same is moved 60 relative to the outer screw 12 through rotation of said outer screw.

With the parts in lowered position and the pinion 9 rotated by the handle 11 through the medium of the stub shaft 10, the gear 3 will be rotated and the rotary movement of the

gear 3 and its part 7 will cause the outer screw 12 to move upwardly very quickly. As the inner screw 16 is held against movement by its telescopic key, the disk 19 and cup-shaped member 5, the inner screw will move upwardly with the outer screw. The spring 20 acts to prevent rotary movement of the outer screw 12. As soon as the load comes upon the saddle 17, however, the weight increases friction on the threads of the outer screw 12 and the part 7 so that said part 12 will rotate with the part 7, and as the inner screw 16 is held against rotary movement by the load, said inner screw will be fed upwardly through the outer screw 12. When the parts are to be returned to normal position, the jack can be turned upside down and the inner screw 16 is turned, so that the pin 30 will drop below the hooks 31 of the disk 19, which will permit the inner screw to be rotated until it is returned to its retracted position within the outer screw 12. If any strain should come upon the parts, the disk would rotate within the cup-shaped member, the ribs 22 riding over the ribs 21 and thus preventing damage to the parts. The ribbed parts thus form a strain relieving clutch, the ribs being of rounded configuration as indicated in Figure 8 of the drawings whereby to permit the ribs to ride, the one over the other, as aforesaid.

As will be seen, the load will come on the saddle and on the part 3, close to the center, and by making the parts 3 and 7 in one piece the cost of manufacture is reduced. By making the key telescopic, there is no interference of this key with the longitudinal movement of the inner screw and the coiled spring tends to move the outer screw upwardly and also keeps it from rotating until the load comes on the inner screw. This spring also places the tension on the disk and holds it against rotation, but permits it to rotate under undue strain by allowing the ribs 22 to ride over the ribs 21. The clutch arrangement between the telescopic key and the disk 19 permits the inner screw to be quickly run back to its normal position.

It is thought from the foregoing description that the advantages and novel features of my invention will be readily apparent. 115

I desire it to be understood that I may make changes in the construction and in the combination and arrangement of the several parts, provided that such changes fall within the scope of the appended claims. 120

What I claim is:—

1. A device of the class described comprising a housing, a cylindrical threaded member rotatably mounted therein, means for rotating the same, an outer screw having its threads engaging the threads of said cylindrical member, an inner screw threaded in the outer screw, means for holding the inner screw against turning about its axis without

interfering with the rectilinear movement thereof, said means including a telescopic key having connection with the inner screw, cooperating means mounted on the frame and 5 tending to prevent rotary movement of the key in one direction, and yieldable means for holding the co-operating means in operative position.

2. A device of the class described comprising a housing, a cylindrical threaded member rotatably mounted therein, means for rotating the same, an outer screw having its threads engaging the threads of said cylindrical member, an inner screw threaded 10 in the outer screw, means for holding the inner screw against turning about its axis without interfering with the rectilinear movement thereof, said means including a telescopic key having connection with the 15 inner screw cooperating means tending to prevent rotary movement of the key in one direction, a pin carried by the key and detachably connecting one of the cooperating 20 means, and yieldable holding means for the 25 cooperating means.

3. A device of the class described comprising a housing, a cylindrical threaded member rotatably mounted therein, means for rotating the same, an outer screw having its 30 threads engaging the threads of said cylindrical member, an inner screw threaded in the outer screw, a telescopic key connected with the inner screw, a cup-shaped member connected with the bottom of the housing and 35 having ribs on the upper surface of its bottom, a disk in the cup-shaped member having ribs thereon engaging the before mentioned ribs, a coiled spring having one end engaging the disk and its other end engaging 40 a part of the outer screw, means for movably connecting the telescopic key with the disk, clutch means connecting the key with the disk, and said clutch means moving to inoperative position when the device is 45 turned upside down and the inner screw rotated a certain distance in one direction.

4. A device of the class described comprising a housing, a cylindrical screw threaded member rotatably mounted in the housing 50 and having a gear formed on its bottom, a pinion engaging the gear, means for rotating the pinion, an outer screw engaging the threads of the cylindrical member, an inner screw passing through the outer screw and 55 means tending to prevent rotary movement of the screws in one direction while permitting rectilinear movement thereof and including cooperating means, one of the cooperating means having detachable connection 60 with respect to the inner screw, the other cooperating means having connection with the housing, and yieldable means for holding the co-operating means in operative position.

5. In a jack, a housing comprising a tubular member and a separate cover plate form-

ing a bottom for the tubular member, means for attaching the cover plate across the lower end of the tubular member, driving means comprising a second tubular member rotatably and co-axially mounted within the first tubular member and provided with a beveled gear at its lower end, said tubular driving member being supported by the cover plate and having a central opening, said cover plate being provided with a central upstanding projection adapted to fit into the opening of the rotatable tubular member to center the same in the housing, a beveled pinion rotatably mounted in the side walls of the first tubular member and making a driving connection with the bevel gear, a lifting member having threaded connection with said driving means, a second lifting member having screw threaded connection with said first mentioned lifting member, and means for preventing relative rotation of the second lifting member in one direction with respect to the housing.

6. In a jack, a housing comprising a tubular member and a cover plate forming a bottom for the tubular member, means for attaching the cover plate across the lower end of the tubular member, driving means comprising a second tubular member rotatably and co-axially mounted within the first tubular member and provided with a beveled gear at its lower end, said tubular member being supported by the cover plate, said cover plate being provided with a central upstanding projection and said rotatable tubular member having a central opening forming a journal for receiving the projection, to center the rotatable tubular member in the housing, said projection comprising a circular centralizing plug secured to the base plate by fastening means extending therethrough, a beveled pinion rotatably mounted in the side walls of the sleeve and making a driving connection with the bevel gear, a lifting member threading with said driving member, a second lifting member threaded with said first mentioned lifting member, and means for preventing relative rotation in one direction of the second lifting member with respect to the housing.

7. In a jack, a housing forming a base comprising a tubular portion and a cover plate closing the lower end of the tubular portion, means for detachably connecting the cover plate to the tubular portion, a driving member having an upstanding tubular portion internally threaded and rotatably and co-axially mounted within the tubular portion of the housing, said driving member being provided with a beveled gear, means mounted in the tubular portion of the housing and comprising a beveled pinion meshing with the bevel gear of the driving member for driving the same, said beveled gear being supported on the base plate of the housing and having

a downwardly extending annular portion defining a journal, a circular plug centrally fixed to the base plate and extending upwardly thereof within said journal whereby the 5 lower end of the driving member may be maintained in co-axial alignment in the housing, said base plate being perforated beneath said plug and fastening means having an outwardly tapered portion extending through 10 said aperture of the base plate and engaging the circular plug to secure same in place upon the base plate, a first lifting member threaded into the internally threaded portion of the driving member, said first lifting member 15 having a second threaded portion, and a second lifting member making screw threaded connection with said second threaded portion, and means forming a splined connection between the base and the second lifting member whereby to prevent relative rotation in one direction therebetween.

8. In a jack, the combination of a housing provided with a threaded driving member and interthreaded telescoping lifting members mounted within said housing for projection therefrom, one of said lifting members meshing with the thread of the driving member, means for preventing rotation of the innermost of said lifting members whereby to effect the automatic projection of at least one of said lifting members upon the operation of the driving member, said means including a clutch releasable to permit relative rotation of said innermost lifting member with respect to the base.

9. In a jack, the combination of a housing provided with a driving member having threaded telescoping lifting members having interthreaded parts, and mounted within said housing for projection therefrom, one of said lifting members meshing with the thread of the driving member, means for preventing rotation of one of said lifting members whereby to effect the automatic projection of at least one of said lifting members upon the operation of the driving member, said means including a manually releasable clutch, to permit rotation of said lifting member.

10. In a jack, the combination of a housing, a driving member, threaded telescoping lifting members having interthreaded parts and mounted within said housing for projection therefrom, one of said lifting members meshing with the thread of the driving member, means for preventing rotation of one of said lifting members whereby to effect the automatic projection of at least one of said lifting members upon the operation of the driving member, and a clutch operable in part by gravity to permit the free turning of at least one of said screw threaded members.

11. In a jack, the combination of a housing, a driving member having threaded telescoping lifting members having interthreaded parts and mounted within said housing for

projection therefrom, one of said lifting members meshing with the thread of the driving member, means for preventing rotation of one of said lifting members whereby to effect the automatic projection of at least one of said lifting members upon the operation of the driving member, and a releasable clutch operable upon the inversion of the jack for permitting the free turning of at least one of said screw threaded members to permit the facile collapse of the jack.

12. In a jack, the combination of a housing, a driving member, threaded telescoping lifting members having interthreaded parts and mounted within said housing for projection therefrom, one of said lifting members meshing with the thread of the driving member, and means for holding at least one of said screw members from rotation during the operation of the driving member whereby to cause the automatic projection of said screw threaded lifting members, said means including devices having interlocking parts disengageable to permit manual rotation of the lifting members whereby the jack may be quickly collapsed.

13. In a jack, the combination of a housing, a driving member, threaded telescoping lifting members having interthreaded parts and mounted within said housing for projection therefrom, one of said lifting members meshing with the thread of the driving member, means for preventing rotation of one of said lifting members whereby to effect the automatic projection of at least one of said lifting members upon the operation of the driving member, said means being manually releasable to permit the free rotation of one of said screw members for collapsing the same by hand.

14. In a screw jack having a threaded extensible member, rotatable drive means for projecting said member from the housing, means normally holding the member against rotation with respect to the housing to cause the automatic projection thereof, said means being operable upon the inversion of the jack to release the member for rotation with respect to the housing.

15. In a jack, the combination of a housing, a driving member rotatably mounted in said housing and provided with a thread, a first lifting member meshing with the thread of the driving member, a second lifting member threadingly engaging the first lifting member, and a connection between the second lifting member and the housing for holding the second lifting member from rotation whereby to cause the automatic projection of the second lifting member, said connection including a clutch releasable upon the complete projection of the said lifting member.

16. In a jack, the combination of a housing, a driving member, rotatably mounted

in said housing and provided with a thread, a first lifting member meshing with the thread of the driving member, a second lifting member threadingly engaging the first lifting member, and a connection between the housing and the second lifting member to prevent rotation thereof whereby to cause the automatic projection of the second lifting member, said connection including a releasable clutch to prevent damage to the jack parts.

17. A multiple screw lift jack having means for preventing rotation of a lifting member whereby to cause an automatic projection thereof upon the operation of the jack, said means including a spring pressed dog clutch releasable in either direction to prevent damage to the jack parts when the extensible member is either in fully extended

20 or fully collapsed position.

18. In a lifting jack, a housing having an upright tubular portion, driving means rotatably supported in said housing, and having a portion formed to provide a bevel gear, means comprising a beveled pinion rotatably supported in the side wall of said housing and having driving connection with said beveled gear portion of the driving member, said driving member having an upstanding tubular portion provided internally with screw threads, a lifting member provided with screw threads in its exterior portions, said screw threads meshing with the internally threaded portions of said driving member, a second lifting member having threaded connection with said first mentioned lifting member, means normally preventing rotation of the second lifting member during the projection thereof, said means being yieldable

40 to permit free rotary movement of the second lifting member relative to the housing when at the outermost limits of its vertical travel.

19. In a lifting jack, a housing having an upright tubular portion, driving means rotatably supported in said housing, and having a portion formed to provide a bevel gear, means comprising a beveled pinion rotatably supported in the wall of said housing and having driving connection with said beveled gear portion of the driving member, said driving member having an upstanding tubular portion provided internally with screw threads, a lifting member provided with screw threads in its exterior portions, said screw threads meshing with the internally threaded portions of said driving member, a second lifting member having threaded connection with said first mentioned lifting member, and means

60 for preventing relative rotation of said second lifting member with respect to the housing, said means co-operating between said second lifting member and the housing and including yielding means operative at the

second lifting member with respect to the housing to permit rotation of the said member whenever it reaches said limits.

In testimony whereof I affix my signature.

FRED J. BULLIS.
